LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

BLOCK-SIGNAL SYSTEM.

1,188,272.

Specification of Letters Patent. Patented June 20, 1916.

Application filed June 1, 1908. Serial No. 435,861.

To all whom it may concern:

Be it known that I, LAURENCE A. HAWKINS, a citizen of the United States, residing at Schenectady, in the county of Schenectady and State of New York, have invented certain new and useful Improvements in Block-Signal Systems, of which the following is a specification.

My invention relates to block signaling systems for electric railways having both track rails conductively continuous for all currents, and its object is to provide a novel signal system, which is reliable in operation, efficient with respect to power consumption, unaffected by the power current in the rails, which defines the blocks with practically the same definiteness as though insulated joints were employed, and in which the amount of apparatus is reduced to a minimum.

I will describe one form of block signal system embodying my invention and will then point out the novel features thereof in claims.

The accompanying drawing is a diagrammatic view showing an electric railway having applied thereto one form of block signal system embodying my invention.

Referring to the accompanying drawing, A represents the track rails of an electric railway, which rails are conductively continuous for all currents, and B represents the third rail or supply conductor to which is connected one terminal of a power generator C. The other terminal of this generator may be connected to both track rails either directly or through a differential choke coil c.

D represents an alternating current generator for the signal current, which may be of any suitable frequency. If the power current is direct, a 50 or 60 cycle generator is well adapted for supplying the signal current.

d represents the line wires transmitting the signal current from the generator D.

E' represent transformers having their primaries connected to line wires d and their secondaries connected at intervals across the track rails. These transformers thus act as sources of signaling current for the track rails. Impedances e and e' are placed in series with the secondaries of these trans-

formers to limit the current drawn from a transformer when a train is standing directly over its secondary connections. These impedances may be either inductive or non-inductive.

G, G' and G² represent impedances which are connected across the rails at points between the supply transformers and which may also be either inductive or non-inductive. These impedances are not connected to directly opposite points on the two rails, but are connected to points which are displaced along the track a short distance, for instance, one hundred feet.

F, F', F² and F³ represent track relays which are shown diagrammatically as of the well known two-phase induction type each comprising a short-circuited secondary f carrying the relay contacts, a winding f² supplied with current independently of the track circuits by its connection to the line wires d through a suitable phase controlling device indicated by the condenser f³, and a second winding f' co-operating therewith to produce the relay torque. The windings f' of two adjacent relays, as, for instance, F' and F², are connected to overlapping rail lengths, as shown in the drawing. Since the amount of overlap may be made anything desired by displacing the terminal connections of the impedance G' the desired amount, each relay winding may be caused to span any desired length of rail, at the same time leaving it impossible for the car of no matter how short a wheel base to stand in a position in which neither relay F' nor F² will be deenergized.

The contacts of relays F and F' are connected in series to control the circuit of the operating mechanism of the signal H, which circuit as here shown is supplied with energy from the signal wires d. Similarly, the relays F² and F³ control the signal H' for the succeeding block.

The direction of traffic is from right to left, as indicated by the arrow. When the blocks are clear, the transformer E supplies alternating current to the track rails, which current flows in both directions from the transformer through the two impedances G and G', and the transformer E', similarly, supplies current to the rails of its block, its current flowing through impedances G' and

G². The transformers E and E' are similarly connected so that the currents from these two transformers flow through impedance G' in parallel. The coil f' of each relay has impressed on its terminals a voltage determined by the amount of current flowing and by the impedance of the short rail length in shunt to which it is connected. The length of rail spanned by each coil is 5 determined by the torque desired in the relay and the amount and frequency of the signal current in the rails. I have found that with 10 4 to 5 amperes at 60 cycles in the rails sufficient torque in the relay can be obtained for 15 satisfactory operation with the length of rail spanned by each relay coil of not more than one hundred feet.

As long as no trains are in the blocks, the 20 relays are energized and the signals stand at clear. Furthermore, a train approaching a block has no effect on the relays except slightly to increase the torque of the relay at the entrance of the block by gradually short-circuiting the track impedance G so as to 25 draw a slightly increased current from the transformer E. As soon as the front wheels of the train, however, pass the first point to which the impedance G is connected, they begin to short-circuit the winding f' of relay F, and as soon as the front wheels have 30 covered the distance spanned by this relay coil, the relay is totally deenergized. The point at which the signal H goes to danger is consequently fixed within the short rail 35 length spanned by the relay winding f'. As long as the train is between transformer E and relay F, relay F remains deenergized, while by the time the front wheels of the train have reached transformer E, relay F' 40 has been deenergized by the short-circuiting of the transformer; consequently, signal H stays at danger until the rear wheels of the train have passed over the short rail length spanned by the track winding of relay F'. 45 As soon as the rear wheels have passed the last point to which impedance G' is connected, relay F' has again reached its full torque, and, in fact, has a slightly increased torque due to the short-circuiting of impedance G' and the somewhat greater current drawn from transformer E, so that signal H then returns to clear.

It will be seen that with a train in a block, any current from an adjacent block that 50 passes the impedance connected across the rails between the blocks, is in the reverse direction to that normally passing through the track winding of the relay of the block which is occupied so that its only effect is to

hold the relay more firmly in its deenergized 60 position.

With the arrangement which I have here shown, the length of rail to which each relay winding f' is connected in shunt may be any desired value, the only limit being the definiteness with which it is desired to fix the point at which the signal will go to danger. At the same time it is impossible for a car 65 of no matter how short a wheel base to stand in a position in which neither relay F' nor 70 F² will be deenergized.

I do not desire to limit myself to the specific connections and arrangement of parts here shown, but aim in the appended claims to cover all modifications which are within 75 the scope of my invention.

Having thus described my invention, what I claim is:

1. In a block signal system, in combination with an electric railway having both 80 rails conductively continuous for all currents, sources of alternating current connected across the rails at intervals, an impedance connected across the rails, at a point between two sources, the points on opposite 85 rails to which the terminals of said impedance are connected being displaced from each other a short distance along the track and a pair of track relays connected in shunt to short over-lapping lengths of the two rails 90 respectively, adjacent to, and on opposite sides of, the impedance, said rail lengths being alone sufficient to provide the necessary drop in potential for operating the relays.

2. In a block signal system, in combination with an electric railway having both 95 rails conductively continuous for all currents, sources of alternating current connected across the rails at intervals, an impedance connected across the rails at a point 100 between two sources, the points on opposite rails to which the terminals of said impedance are connected being displaced from each other a short-distance along the track, a pair 105 of track relays connected in shunt to short over-lapping lengths of the two rails respectively adjacent to and on opposite sides of the impedance, said rail lengths being alone sufficient to provide the necessary drop in 110 potential for operating the relays, and a pair of signals controlled by said relays respectively.

In witness whereof, I have hereunto set my hand this 28th day of May, 1908.

LAURENCE A. HAWKINS.
